Primary Examiner — T. Chase Nelson*Assistant Examiner* — Ania Aman*(74) Attorney, Agent, or Firm* — The Belles Group, P.C.(57) **CLAIM**

The ornamental design for an intake manifold for an engine, as shown and described.

DESCRIPTION

FIG. 1 is an elevated rear-right perspective view of an intake manifold for an engine according to the new design;
 FIG. 2 is an elevated rear-left perspective view thereof;
 FIG. 3 is an elevated front-left perspective view thereof;
 FIG. 4 is an elevated front-right perspective view thereof;
 FIG. 5 is a rear plan view thereof;
 FIG. 6 is a front plan view thereof;
 FIG. 7 is a right-side plan view thereof;
 FIG. 8 is a left-side plan view thereof;
 FIG. 9 is a top plan view thereof; and,
 FIG. 10 is a bottom plan view thereof.

UNITED STATES PATENT AND TRADEMARK OFFICE
CERTIFICATE OF CORRECTION

PATENT NO. : D733,187 S
APPLICATION NO. : 29/479651
DATED : June 30, 2015
INVENTOR(S) : Bink et al.

Page 1 of 10

It is certified that error appears in the above-identified patent and that said Letters Patent is hereby corrected as shown below:

On the title page, showing the illustrative figure, should be deleted and substitute therefor the attached title page.

In the drawing sheets, consisting of figs. 1-10, should be deleted to be replaced with the drawing sheets, consisting of figs. 1-10, as shown on the attached page.

Signed and Sealed this
Ninth Day of February, 2016

Michelle K. Lee
Director of the United States Patent and Trademark Office
